DOOR CONTROL

Harvey L. F. Nettleton, Milford, and Walter J. Milestan, Bridgeport, Conn.

Application September 12, 1949, Serial No. 4,958

Term of patent 7 years

(Cl. D10—7)

To all whom it may concern:

Be it known that we, Harvey L. F. Nettleton and Walter J. Milestan, citizens of the United States of America, residing at Milford and Bridgeport, respectively, in the counties of New Haven and Fairfield, respectively, and State of Connecticut, have invented a new, original, and ornamental Design for a Door Control, of which the following is a specification, reference being had to the accompanying drawing, forming part thereof.

Figure 1 is a top plan view of a door control showing our new design;

Figure 2 is a side elevational view thereof, and Figure 3 is an end elevational view of the same.

We claim:

The ornamental design for a door control, as shown.

HARVEY L. F. NETTLETON.
WALTER J. MILESTAN.
